UNITED STATES PATENT OFFICE.

JAMES P. SCOVILL, OF WYOMING, OHIO, ASSIGNOR OF ONE-HALF TO C. H. FOSTER, OF TROY, NEW YORK.

TOBACCO-STEMMING MACHINE.

1,153,962.

Specification of Letters Patent. Patented Sept. 21, 1915.

Application filed February 24, 1908. Serial No. 417,546.

To all whom it may concern:

Be it known that I, JAMES P. SCOVILL, a citizen of the United States, residing at Wyoming, in the county of Hamilton and 5 State of Ohio, have invented certain new and useful Improvements in Tobacco-Stemming Machines, of which the following is a specification.

My invention relates to a tobacco stem- 10 ming machine.

In my present improvement I have retained much of the mechanism and its respective organization already shown, described and claimed by myself and another 15 in an application filed March 19, 1907, Serial No. 363,813. Since the said application has been filed, I have discovered certain facts in the handling of tobacco leaf which have led to the developments of the im- 20 provements forming the subject-matter of this application. In the said former machine it was the preferable, although not the essential, mode of procedure to stem the leaf by presenting the butt first to the strip- 25 ping mechanism. In the present invention, I reverse this presentation while retaining much of the stem gripping and leaf strip- 30 ping mechanism of the former machine. I have found my present machine to be prac- tically adapted to all grades and conditions 35 of tobacco, and able to meet all the requirements of every-day usage. The super- 40 ior efficiency of this machine is attrib- 45 uted to the novel features constituting the subject-matter of this application, by means 50 of which I insure an initial tear of the leaf near the tip and upon each side of the stem, without danger of breaking the stem and without removing the tip of the leaf from the custody of the gripping mechanism; 55 after its initial tear I pass the leaf on to the stripping mechanisms which may be, and preferably are, of the character described in my said prior application. Thus it will be seen that my present method of stemming 60 contemplates holding the tip of the leaf firmly in the grip of the carrier and presenting the tip portion of the leaf to a stem locating and leaf tearing mechanism, of a sensitive character and delicate operation, 65 adapted to safely and surely operate upon that tender portion of the leaf and stem, imparting the initial tear against the grain without breaking the stem, the carrier then 70 presenting the leaf to stripping mechanism

of harsher character, which will complete the stemming by continuing the tear against the grain.

The primary purpose of this invention is therefore to effectively clean the tip end of 60 the stem without breaking the tender stem, and by a method adaptable to the multi- titudinous variations of leaf tobacco in con- dition and character.

While I show preferred mechanical de- 65 vices to take up the stripping action after this sensitive, initial, partial stripping, it is possible to devise a very wide range of strippers which could then be utilized to complete the stripping, or it could even be 70 done by hand, for the tender portion of the leaf having been stripped and the stem preserved, a continued tearing strain against the grain will complete the operation.

These and other features of the invention 75 will be more fully set forth in the descrip- tion of the accompanying drawings, forming a part of this specification, in which:

Figure 1 is a top plan view of my im- 80 proved tobacco stemming machine. Fig. 2 is an enlarged detail view of the initial strippers. Fig. 3 is a sectional elevation of the feed carriers. Fig. 4 is a side elevation of the driving mechanism for the initial strippers, the strippers being shown in sec- 85 tion. Fig. 5 is a side elevation of the de- flecting rolls. Fig. 6 is an end elevation of the toothed guard rolls of the main stripping mechanism. Fig. 7 is a side elevation of the main strippers 90 with their supporting frame partly in sec- tion. Fig. 8 is a side elevation of the pull rolls with their supporting frame, shown partly in section. Fig. 9 is a section on line α , α , Fig. 1. Fig. 10 is an end elevation 95 illustrating the gearing of the main strippers. Fig. 11 is an end elevation of the cutters. Fig. 12 is a side elevation of the same. Fig. 13 is a side elevation of the car- 100 riers, the strippers, initial and main, being omitted, but indicated as to position.

It will facilitate a clear understanding of this invention to first take, as it were, a bird's-eye view of the entire device, return- 105 ing later for details.

Looking at Fig. 1, 1 is the table upon which the machine rests. 2 is a leaf feeder composed of a number of spaced endless carriers of the usual character, upon which the leaves are laid transversely. The leaves are 110

fed along toward the machine proper until they are individually caught up by the higher speeded saw wheel or pick-up 3, which spaces and separately introduces the leaves between the pairs of stem gripping endless carriers 4, (see Fig. 3), which grasp the tip end of the leaf. This gripped tip of the leaf remains within the grasp of this carrier mechanism throughout the stripping operations and is finally cut off from the clean stem. From the position in which the leaves lie upon the initial feeders 2, it is to be understood that the stem grippers 4 travel in a line substantially at right angles to the original positions of the stems. The various strippers are angularly disposed relative to the travel of the carriers 4.

To strip at all, it is essential to preserve intact the stem. It should be understood that in practice the leaf arrives in all conditions of wetness and dryness, and that all varieties of leaf are operated upon, and in every case, the stem, particularly at the tip, is infolded within the leaf at this point, also the leaf and stem are both tender. It is necessary to infallibly clean the stem tip under all of these conditions by a mechanical device, adapted to impart an initial tear or cut against the grain. This mechanism must be of such a character that while this delicate operation is proceeding, the stem will not be broken, but will be retained in the grip of the stem carrier, and if desired, passed on to strippers of a harsher organization which will readily complete the operation if it has thus been properly started. These initial stem finding leaf strippers are shown in their preferred form in Fig. 2 in detail, and in a plan view in Fig. 1. They consist, as shown, of two circular oppositely rotating disks 5, the peripheries of which are armed with pins 6, set far enough apart to permit of a safe passage of the stem between them. These pins are so set on the opposing disks that they do not impinge upon one another, and at their line of intersection they cannot either entirely block the passage of the stem or injure it in its passage. The disks are disposed at the forward end of the carrier and obliquely thereto, not for the purpose of making a transverse cut across the web of the leaf, but to pierce the leaf at points on each side of the stem, so as to tear or strip parallel with the stem as the leaf is drawn forward. Their rotation corresponds in general direction of feed, to that of the stem gripping carriers respectively, so as to always present a continuous access to the leaf, but they are preferably rotated at a lower rate of speed, in order to create a degree of opposition to the passage of the leaf sufficient to result in a tearing strain against the grain. Adjacent to the rear edges of these disks 5 is a pair of rolls 7 provided with worms 8 running down and

terminating on the conical ends 9, and leading away from the gripped portion of the stem, in order to rapidly deflect the free end of the leaf from the line of action of the pins. It will be observed that the rotating pin disks are set at an acute angle, relative to the main carrier 5, so that the pins rotate in a plane diverging from the plane of travel of the stem gripping carrier 5. The tip end of the leaf is held between carriers 75 so that it cannot be stripped by the pins or first set of rolls. The pins perforate the tip end of the leaf without injuring the stem, and impart an initial stripping action longitudinally of the stem and adjacent to 80 the gripped portion of the tip. This starts the stripping operation at the fragile portion of the leaf toward the butt, and a second set of rolls continue this stripping, clear to the butt, but leaving that portion of the tip, 85 which is gripped by the carrier unstripped. As I have already described in my said prior application, rolls provided with this character of spiral way present a continuous access to a stem drawn toward them axially. 90

This initial stripping mechanism operates as follows:—As already explained, the tip of the leaf is firmly gripped between the carriers 4, until it is drawn between, what I have termed, the stem finding leaf strippers, which consist in detail of the pin disks 5. As these disks feed in unison with the stem carrier, they present a continuous access to this adjacent portion of the tobacco leaf, and the oppositely disposed pins coming together alternately impinge upon opposite sides of the leaf on either side of the stem and bring to bear a tearing strain which acts upon the leaf in opposition to the pull of the stem carrier, as well as in opposition to the natural grain of the leaf, so that the leaf is thereby initially ruptured at this point, and a tearing or stripping action along the stem results, but without breaking the stem. By the time this sufficient initial stripping action has been given at the tip end of the leaf, the leaf has passed from between the efficient portions of the disk, and has been delivered into the open ends of the rolls 7, which rapidly deflect the free end of the leaf from the pins. It is to be understood that these rolls are relatively high speeded, so as to insure the rapid carrying away of the leaf from the proximity of the pin disks, the tip of the stem, of course, still being retained in the grip of the carriers 4. The rolls 7 are considerably spaced, so that they readily pass both the stem and leaf between them, and lead them away from the pin wheels, but without any material stripping action being intended. The stem gripping carrier now draws the stem and the partially stripped leaf in between the main stripping rollers 10, 11, one of which is 125 130

preferably provided with a spiral stem-way having stripping instrumentalities, such as are shown in my former case. These main stripping rollers 10, 11, are rotated in opposite position to the pull of the stem gripping carrier, and take up and complete the stemming commenced by the members 5. In practice, I prefer that one of these main stripping rollers 10, shall be provided with axial ribs 12, on its periphery, instead of a stem-way, for the reason that this formation has a greater leaf repulsion influence than the stem-way character of rolls. It also prevents any bunching of the leaf which tends to break the stem. These ribs rapidly and forcibly eject stripped leaf portions, which have a natural tendency to follow the stem in its flight through the rollers. Adjacent above and below these main stripping rollers 10 and 11 respectively, is a second pair of rollers 13 and 14, which are virtually guards. They preferably have a higher surface speed than the stripping rollers, and they are so disposed as to effectively prevent the leaf from becoming wrapped or entwined between the gripping rolls. The upper stripping roll and the upper guard roll have the same direction of rotation, and the lower stripping roll and lower guard roll likewise have a similar direction of rotation. By these means the stem invariably continues its forward flight while the stripped leaf is thrown backward and discharged through an opening in the table located between the rollers 7 and the stripping rollers.

15, 16 represent a pair of pull rollers in rear of the stripping and guard rollers, which assist in pulling the stem, and in maintaining the alignment. They are set at such an angle to the stripping rollers as to cause their pull to substantially coincide with the pitch of the stem-way.

In order to maintain a most efficient hold upon the stem issuing from the rear end of the stem-way, the rear ends of the pull rollers form an acute angle with the rear ends of the stripping rollers. The shafts of said pull rolls are laterally extended and driven from a point on the off-side of the carriers 4, in order to permit of this angular impingement of the pull and stripping rollers, the shafts of the latter rolls being oppositely extended and are driven from the other side of the carrier 4.

Preferably, the rollers 10 and 13 are flexibly supported relative to their lower rollers in order to yield to inequalities.

It will, of course, be understood that the high speeded rolls 7 rotate in the same relative directions as the stripping rollers, whereby the pitch of the spiral rapidly carries the leaf away from the neighborhood of the pin wheels. It follows from this arrangement and operation that any broken

stems which may be contained in the original charge of leaves will be forcibly repelled and not permitted to enter the machine or become mixed with the leaf product. It is only necessary to carry the spirality of the 7 rolls 7, far enough to deliver the stem and leaf to position out of danger when they will lie upon the reduced or stem portions 18 of the rolls in position to coöperate with the stripping mechanism beyond, and in which position the rotative influence of the stems of the rollers is practically *nil*. The rear ends of these rollers 7 are provided with peripheral contacting rolls 19, 20, mounted on their common shafts 18. By this means any broken stems contained in the original package and which would be crowded toward rolls 19, 20, by the succeeding charge, are positively ejected at this point, and not permitted to enter the stripping parts of the machine.

The last step consists in cutting off the gripped tip of the leaf from the cleaned stem, which is performed by the cutting mechanism 17, (see Figs. 11 and 12) to be later described in detail.

Having thus broadly outlined the construction and operation of the machine in its entirety, it will be necessary to describe the less important details and identify the parts shown by the drawings.

The feeding mechanism, as shown, consists of the following parts:—21 represents a pulley driving wheel (see Figs. 1 and 12), on shaft 22, having a gear wheel 23, intermeshing with gear wheel 24 on shaft 25. Shaft 22 carries a sprocket wheel 26, and shaft 25 has a sprocket wheel 27 forming the rear sprocket drive for the carrier chains 4. Shaft 22 carries the cutting disks 28, 29, clamped together upon a separating blank 30, so as to form a peripheral groove between them, into which the stem is transversely crowded by the intermeshing saw-toothed cutter 31, this construction affording a shearing action which is entirely reliable in severing the stem. The cutter 31 is mounted on shaft 25.

32 represents a guide or bridge adjacent to the carrier 4 and the cutters, (see Fig. 11), which holds the stem to this cutting action. The upper sprocket chain 4 passes over a forward sprocket wheel 33 on shaft 34, the lower sprocket chain passing over a wheel 35 on shaft 36, (see Figs. 1 and 13). Sprocket wheels 26, 27, 32, 34, drive carriers 4.

The primary feeding carriers 2 are operated as follows:—Shaft 36 has a series of sprocket wheels 37 fixed thereon. 38 represents the forward shaft having sprocket wheels 38, 39, thereon. The chains 2 pass over the sprocket wheels 37 and 39. The shaft 36 has a toothed wheel 40 thereon having a higher surface speed than the chains 12

2, and serving to space the stems in transmitting them to the carriers 4, (see Figs. 1, 3 and 13). By the means just described, the carriers 2 feed the leaf primarily to the machine.

For driving the first or more sensitive stem tip cleaner, I provide the following mechanism:—On the end of shaft 36 is a gear wheel 42 intermeshing with gear wheel 43, on sleeve 44, loose on shaft 34. 45 represents a pulley wheel on sleeve 44 driving pulley wheel 46, on shaft 47, by means of belt 48. On the inner end of shaft 47 is a beveled gear wheel 49, driving gear wheel 50, on shaft 51, (see Figs. 1 and 4). Gear 50 drives gear 52 on shaft 53. Shaft 53 carries the upper pin disk 5 and shaft 51 carries the lower pin disk.

For driving the pull rolls 15, 16, (see Fig. 8), roll 16, which is preferably ribbed, is on shaft 54 having bearings in the frame 55 and driven by belt wheel 56. Roll 15, which is preferably felt or rubber-faced is on shaft 57, having bearings in frame 55.

25 58 represents a gear wheel on shaft 54 driving gear wheel 59 on shaft 57.

For driving rolls 7, stems 18 are outwardly projected and have bearing in a frame 60, (see Fig. 5). On the end of these 30 stems are intermeshing gear wheels 61, 62, one of which is driven by pulley wheel 63.

For driving the main stemming rolls 10, 11, roll 10 has an outwardly extended shaft 65 carrying gear wheel 66, roll 11 has similar 35 shaft 68 carrying intermeshing gear wheel 69.

70 represents driving pulley wheel on shaft 68.

Roll 13 has shaft 71, and roll 14 has similar shaft 72. These shafts have bearings in a frame 73, (see Fig. 7). Gear wheel 69 drives gear 74, which in turn drives gear 75 on shaft 72. Gear wheel 66 drives gear 76, which drives gear 77 on shaft 71, (see 45 Fig. 10).

78 represents a guard for the rear end of the upper carrier chain 4, (see Fig. 11), this chain preferably passes over the sheave 79, (see Figs. 1 and 13).

50 I have preferably interposed between the primary feeders 2 and the pin disks 5 a guide 80 adjacent to the front end of the lower carrier 4, which assists in delivering the leaves properly to the action of the 55 disks 5.

81 represents a pair of guides to assist in properly delivering the stem from the disks 5 into the open ends of the rolls 10, 11.

In order to give a proper gripping tension 60 to the opposing surfaces of the carriers 4, I preferably provide the mechanism shown in detail section, Fig. 9, and also in Figs. 1 and 13. It will be unnecessary to describe this in particular detail, as it was disclosed in 65 my said former application. It consists of

an elongated tension block 82 supported at each end by a spring actuated plunger 83, the lower loop of the upper carrier 4 passing under and being influenced by the tension of this bearing block 82, which has a 70 kind of tilting spring deflection, the functions of which were described in my said former application.

It will be understood from this description that the driving mechanism operates 75 the feeders 2, the disks 5, the carriers 4 and the pull rolls 15, 16, in a direction to feed the stems from the front to the rear of the machine, and the rollers 8, 10 and 11 are rotated in the direction opposed to the feed of the 80 stems. It is obvious that the provision for securing these drives may be variously modified without departing from the principles of the invention.

It will be observed that the worm or spiral 85 rolls 8 are placed in front of and extend parallel with the stripping rolls 10, 11, and they have a useful function in this correlation independent of their co-operative relationship to the pin wheels. As the carrier 90 draws the leaf between rolls 10, 11, the trailing or ungripped end has been caught by rolls 8, and carried laterally away from the gripping belts, so that the stem is extended, and held in this position for treat-

ment, the advancing end being gripped, the trailing end being moved laterally by rolls 8 to hold this end in alinement with the gripped end, while rolls 10, 11, operate upon the leaf between these ends. Were it not 100 for this provision, or its equivalent, the trailing ends emerging from the treating rolls would lag, and the stems would bend upon themselves. The angle of the carrier will draw the stems endwise between rolls 105 10, 11, assisted by the spiral formations thereof, and the rolls 8 feed laterally the free ends of the leaves at an appropriate speed, so that the leaves are presented for treatment longitudinally of their stems. 110

Having described my invention, I claim:—

1. In a tobacco stemming machine, a stem gripping carrier, a stem finding and tip stripping mechanism consisting of rotating pin points disposed obliquely relative to the carrier and rotating in the general direction of carrier travel to advance the leaf and adapted to initially puncture and strip the leaf against the grain upon each side of the stem near the tip. 115

2. In a tobacco leaf stemming machine, a tip gripping carrier, and mechanism disposed obliquely relative to the carrier rotating in the general direction of carrier travel but at a lower speed, and adapted to transiently interpose leaf puncturing and stripping points to the passage of the gripped leaf upon opposite sides of the stem at the ungripped portion of the tip. 125

3. In a tobacco leaf stemming machine, 130

comprising main stripper, a tip gripping leaf carrier holding one end of the leaf throughout the stripping, and mechanism disposed obliquely relative to the carrier and operating upon one side of the carrier in the same general direction of travel to advance the leaf, but moving slower to interpose tearing points upon each side of the tip of the stem during its passage, whereby the leaf is initially stripped at its tip against the grain and delivered to said main strippers.

4. In a tobacco leaf stemming machine comprising main strippers, a tip gripping leaf carrier holding one end of the leaf throughout the stripping, and mechanism disposed obliquely relative to the carrier and operating upon one side of the carrier in the general direction of carrier travel to advance the leaf, but moving slower to angularly interpose tearing points upon each side of the tip of the stem during its passage, whereby the leaf is initially stripped at its tip against the grain and delivered to said main strippers.

5. In a tobacco stemming machine, a stem gripping carrier, a relatively angularly disposed pair of rotary members, having a plane of rotation obliquely disposed relative to the carrier having the same general direction of travel, and having tearing points adapted to operate upon opposite sides of the stem and impart an initial strip of the leaf against the grain while the leaf is being advanced to other stripping instrumentalities.

6. In a tobacco stemming machine, a stem gripping carrier, a relatively angularly disposed pair of rotary members, having a plane of rotation obliquely disposed relative to the carrier, and mechanism adapted to initially strip the leaf upon each side of the stem, and means for rapidly deflecting the ungripped portion of the leaf from the line of action of the said initial tearing devices.

7. In a tobacco stemming machine, a stem gripping carrier, a pair of relatively angularly disposed rotary members having peripheral points adapted to puncture and strip the leaf upon opposite sides of the stem while it is under the grip of the carrier, said members having the same general direction of carrier travel but moving slower to impart a stripping counter-drag to the draw of the carrier.

8. In a tobacco stemming machine, a stem gripping carrier, a pair of relatively angularly disposed rotary members having peripheral points, the rotary members having a plane of rotation obliquely disposed relative to but in the general direction of the carrier travel and adapted to operate upon opposite sides of the stem adjacent to its gripped portion and strip against the grain

while the stem is advanced by the carrier, substantially as described.

9. In a tobacco stemming machine, a stem gripping carrier, an angularly disposed pair of pin disks disposed at one side of the front end of the carrier and operating obliquely thereto, and a roll having formations adjacent to the pin wheels, adapted to rapidly deflect the ungripped portion of the leaf from the line of action of the disks.

10. In a tobacco stemming machine, a stem gripping carrier, an obliquely disposed stem tip cleaning mechanism having a rotative operation in the general direction of and slower than the feed of the carrier, stripping mechanism for the other end of the leaf having a rotative operation the reverse of the feed of the carrier and at a higher speed.

11. In a tobacco stemming machine, a stem cleaning mechanism operating near the tip, a main stripping mechanism operating on the medial portion of the stem toward the butt, and a carrier mechanism adapted to grip one end of the leaf and drag the stem sequentially through the said stemming mechanisms, said stem cleaning mechanism operating in a general direction of travel of said carrier mechanism.

12. In a tobacco stemming machine, a stem gripping carrier, an angularly disposed pair of stemming rolls, and means in front of said rolls for catching the free ends of the leaves and leading them laterally away from the carrier.

13. In a tobacco stemming machine, a stem gripping carrier, an angularly disposed pair of stemming rolls, and a spiral roll in front of the stemming rolls for feeding the free ends of the leaves laterally away from the carrier.

14. In a tobacco stemming machine, a stem gripping carrier, an angularly disposed leaf stemming instrumentality, and means in front thereof for feeding the rear or free ends of the leaves laterally away from the carrier in a direction of movement appropriate to the progressive leaf treatment.

15. In a tobacco leaf stemming machine, a stem gripping carrier, an angularly disposed leaf stemming instrumentality, and a similarly disposed spiral roll in front of said instrumentality for carrying the rear or free ends of the leaves in the direction of treatment.

16. In a tobacco leaf stemming machine, a stem gripping carrier, an angularly disposed pair of leaf stemming rolls having their inner ends adjacent said carrier and being formed with a spiral instrumentality extending in the direction of treatment, and a spiral roll in front of said treating rolls, the inner end being placed to catch the free or rear ends of the leaves and feed them laterally in the direction of treatment.

17. In a tobacco leaf stemming machine, a gripping carrier for the advancing ends of the leaf, a feeding instrumentality for the rear or free ends of the leaves carrying them laterally away from the carrier, and means for stemming the leaf intermediate the carrier and feeder.

In testimony whereof, I have hereunto set my hand.

JAMES P. SCOVILL.
